UNITED STATES PATENT OFFICE.

OSCAR A. BRONSON, OF MINNEAPOLIS, MINNESOTA.

DESIGN FOR A COVER FOR AN ELECTRICAL SWITCH BOX.

Application filed April 4, 1928. Serial No. 26,123. Term of patent 3½ years.

To all whom it may concern:

Be it known that I, OSCAR A. BRONSON, a citizen of the United States, residing at Minneapolis, in the county of Hennepin and State of Minnesota, have invented a new, original, and ornamental Design for Cover for an Electrical Switch Box, of which the following is a specification, reference being had to the accompanying drawing, forming part thereof.

Figure 1 is a face view of a cover illustrating my design.

Figure 2 is a sectional view taken on line 2—2 of Figure 1.

I claim:

The ornamental design for a cover for an electrical switch box, as shown.

OSCAR A. BRONSON.
